Joseph Ives of Bristol, Connecticut
Sisters' Salve

The Schedule referred to in their letter Patent and making part of the same containing a description in the words of the said Joseph Ives himself of his improvement in the formation of the rolling pinions & pinion wheels in clocks.

To all people whom these presents shall come, Joseph Ives of Bristol in the County of Hartford and State of Connecticut Gentleman sends Greeting - Be it known that the said Joseph Ives has invented, constructed, made and applied to use a new and usefull improvement in the formation of the rolling pinions and pinion wheels, used in the construction of the common house clocks, specified in the words following viz: This improvement in the formation of the rolling pinions consists in making the pinions wholly of one piece of metal or wood, instead of two pieces as formerly used. The rolling pinions as heretofore used still in use, in the construction of Common House clocks, are made to turn on Posts. The pinion head or block in which the pinions turn is made of a solid piece of wood or metal, and turned down in the middle so as to make a space for the pinions to turn in, leaving a shoulder at each end of the block. Holes or small sockets are made thro' each of these shoulders, and the pin or small rod for the pinions as passed thro' these holes in the shoulders, and at the same time thro' the pinions, being tight in the pinions and loose in the holes in which they are to turn. The ends of these pins or rods forming the points of the pinions. My rolling pinions are made each of a single piece of metal or wood without any pin or rod through them, and roll or turn on sockets made to fit them in, and pieces of what I term the pinion head, or wheel as hereafter described. I have two modes of making my rolling pinions as may be seen by the mode of accompanying this application. One mode is to make the pinions of a regular form and to end & place

end and in sockets, made to fit them in, but not thru the head pieces of the pinions, head, or wheel before named, in which sockets, the pinions roll when the wheel is moving. These sockets are made larger than the ends of the pinions, so as to give room for the pinions, to roll in the sockets. By the sockets not being made through the head pieces, the pinions are confined, so that they cannot get out of place endwise. The other mode is to form pivots at each end of the pinions by turning the ends down small enough for that purpose, and have these pivots turn in holes or small sockets, made to fit them, in or thru the head pieces before named. The pinions, turn on the pivots in these sockets or holes, and are confined by shoulders in the pinions formed by turning down the pinions as before stated, so that they cannot get out of place endwise. What I call the pinion head, or wheel being that part in which the pinions roll or turn, is made by forming & fixing on a shaft or arbor two round pieces of metal, or wood called head pieces - about the length of the pinions apart, one of which head pieces has a small cylinder, being a part of the head piece, and extending from its centre on the inside, on the shaft or arbor the length of the pinions, with a small shoulder made on the farther end of it, on which cylinder and to the shoulder the other head piece, or end of the pinion head is fixed, and is called the cap of the pinion head or wheel. The arbor or shaft passes thru the centre of both pinion head pieces, and cylinder which forms a part of one of them as before stated, and they are all confined to, and made tight on the arbor or shaft. The holes or sockets for the pinions to roll or turn in, are made in these head pieces, and that called the cap is placed on and fastened to the cylinder after the pinions are placed in the sockets of the other head piece.

The benefit of my improvement in the rolling pinions is that they can be made with less labor, and expense, perform with much less friction, and are not as liable to get out of repair.

75294

In testimony that the above is a true specification of my
said improvement as above described, I have hereunto set my
hand and seal this 10th day of March Anno Domini 1833.
